CLAIM

The ornamental design for an article carrier blank, substantially as shown and described.

DESCRIPTION

FIG. 1 is a top plan view of an article carrier blank embodying my new design;

FIG. 2 is a side elevational view looking in the direction of the line 2—2 of FIG. 1;

FIG. 3 is a top plan view of a modification of the article carrier blank shown in FIG. 1;

FIG. 4 is a side elevational view looking in the direction of the line 4—4 of FIG. 3;

FIG. 5 is a top plan view of another modification of the article carrier blank shown in FIG. 1; and

FIG. 6 is a side elevational view looking in the direction of the line 2—2 of FIG. 5.

The bottom plan views of the embodiments shown in FIG. 1 and the modifications shown in FIG. 3 and FIG. 5 are substantially the same in appearance as the top plan views related thereto.

The article carrier blank is constructed of material of conventional thickness, and the dashed lines in the drawing represent score lines.
